(57) **CLAIM**

The ornamental design of a keybox cover, as shown.

DESCRIPTION

FIG. 1 is a perspective view of the invention, including the keybox environmental structure.

FIG. 2 is a front elevation view of the invention.

FIG. 3 is a rear elevation view of the invention.

FIG. 4 is a left side elevation view of the invention.

FIG. 5 is a right side elevation view of the invention.

FIG. 6 is a top plan view of the invention; and,

FIG. 7 is a bottom plan view of the invention.

The broken lines in FIG. 1 showing a key box depict environment, which forms no part of the claimed design. The remainder of the broken lines depict stitching, which forms no part of the claimed design.
